(57) **CLAIM**

The ornamental design for a Stringed Musical Instrument as shown and described.

DESCRIPTION

FIG. 1 is a top perspective view of my new design for a stringed musical instrument.

FIG. 2 is a front view of the stringed musical instrument of FIG. 1.

FIG. 3 is a back view of the stringed musical instrument of FIG. 1.

FIG. 4 is a right side view of the stringed musical instrument of FIG. 1.

FIG. 5 is a left side view of the stringed musical instrument of FIG. 1.

FIG. 6 is a top view of the stringed musical instrument of FIG. 1.

FIG. 7 is a bottom view of the stringed musical instrument of FIG. 1.

Broken lines in FIGS. 1-7 are used to illustrate environment and form no part of the claimed stringed musical instrument design.

The stringed musical instrument is shown with symbolic breaks in its length and width. The appearance of any portion of the article between the break lines form no part of the claimed design.
